Inventor;

James Warren Davis

United States Patent Office.

JAMES WARREN DAVIS, OF WASHINGTON, DISTRICT OF COLUMBIA.

Letters Patent No. 61,724, dated February 5, 1867.

IMPROVED BED BOTTOM.

The Schedule referred to in these Letters Patent and making part of the same.

TO ALL WHOM IT MAY CONCERN:

Be it known that I, JAMES WARREN DAVIS, of the city of Washington, in the District of Columbia, have invented new and useful improvements in Spring Bed Bottoms; and I do hereby declare the following to be a full and exact description of the same, reference being had to the accompanying drawing, making part of this specification, and in which—

Figure 1 is a bottom view of my improvements; and

Figure 2, a longitudinal section of the same in the line $z z$, fig. 1.

Similar letters of reference indicate corresponding parts in the two figures.

My invention consists in the use of two sets of wooden springs, the upper ends of which are securely held on movable bars, whilst their lower ends, interlocking each other, play through mortises in sliding bars, and are entirely free.

In the drawings, A is the head end and B the foot end of a frame, constructed in two pieces, hinged together at a , and having fastened to it the mattress C. D D' are braces, holding each of the two parts A B together. On each side of the frame, near the head and foot-boards E E', are pivoted plates b b', each two opposite ones bearing between them bars F F', which are pivoted to the lower ends of the plates b b'. To the upper side of these bars F F' the upper ends of the wooden springs G G' are securely fastened, their lower ends interlocking each other, and passing through mortises H H' in guide-bars c c'. The ends of these latter cross-bars are provided with pins e e', which move in slots d d' laterally, and also allow the bars c c' to turn around their own axes, as clearly shown in fig. 2. When pressure is exerted on the bed it tends to straighten the curved springs, and consequently to elongate them; they having free play through the mortises H H', the springs are thus prevented from breaking, which is frequently the case with wooden springs confined at both ends. A very free play is allowed these springs by means of the bars F F', which are pivoted and have a lateral movement. Should any of the springs break it is very easy to replace them. After loosening them from the bars F or F', they are drawn out and replaced by new ones. The cross-bars c c', being swivelled so as to turn on their own axes, enables them to turn when the springs straighten, and thus follow every movement of the same, guiding and supporting them without having any tendency to break them. I construct my bed frame in two parts, so as to enable the head end to be raised and lowered according to the desire of persons using them. When raised, two legs I I', which are hinged to the frame, retain it in position. I form the slots d d' either in the frames A and B, or cast or otherwise form them of metal, and attach them by nails or screws to the frame. I propose to use my springs not only in bedsteads, but also in sofas, lounges, railroad-car seats, and wherever I can employ them.

Having thus described my invention, what I claim as new, and desire to secure by Letters Patent, is—

1. The curved wooden springs G G' interlocking with each other, secured at their upper ends, and having their lower ends free, which ends pass through slots in guide-bars c c', substantially as described.
2. The guide-bars c c', provided with mortises H H', and pins e e', working in slots d d', substantially as described.
3. The plates b b', in combination with the pivoted head and foot-bars F F', for the purpose and in the manner described.
4. The combination of the wooden springs G G', bars F F', plates b b', guide-bars c c' provided with mortises H H', and pins e e', slots d d', and mattress C, substantially as and for the purpose set forth.

JAMES WARREN DAVIS.
